WATERPROOF COVER FOR UMBRELLAS

Jacob Weisblatt; Brooklyn, N. Y.

Application May 11, 1954, Serial No. 428,903

6 Claims. (Cl. 135—33)

This invention relates to an umbrella protector including a waterproof sleeve that fits over the folded canopy portion of an umbrella, cuff means at one end of the sleeve engageable about the staff of the umbrella, and a collar at the other end of the sleeve providing a weight to hold the sleeve in protective relation to the umbrella.

Among important objects of the invention are the following:

First, to facilitate the application of the protector to conventional umbrellas;

Second, to reduce the manufacturing cost of the protector;

Third, to provide an improved interlock between the cuff and collar, in one form of the device;

Fourth, to simplify the disengagement of the cuff and collar in said form; and

Fifth, to permit application of the device to any of various umbrellas without necessity of modification or redesign of said umbrellas.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of an umbrella equipped with the protector.

Fig. 2 is a fragmentary view of the umbrella opened for use, the protector being shifted to inoperative position.

Fig. 3 is an enlarged transverse sectional view on line 3—3 of Fig. 2.

Fig. 4 is a fragmentary perspective view showing the cuff opened.

Fig. 5 is an enlarged, fragmentary, perspective view of the collar end of the device.

Fig. 6 is a detail sectional view of the collar, on line 6—6 of Fig. 5.

Fig. 7 is a detail sectional view of the cuff on line 7—7 of Fig. 3.

Fig. 8 is a perspective view of a modified form, partly broken away.

Fig. 9 is a fragmentary perspective view of another modification.

Fig. 10 is a sectional view substantially on line 10—10 of Fig. 9.

Fig. 11 is a sectional view substantially on line 11—11 of Fig. 10.

Fig. 12 is an enlarged sectional view on line 12—12 of Fig. 11.

Fig. 13 is an enlarged detail sectional view on line 13—13 of Fig. 12.

A conventional umbrella 14 has been shown, having a handle 16, and a staff 18. The protector 20 constituting the invention is shown in Fig. 1 in protective relation to the folded umbrella, and in Fig. 2 in folded-back position to permit opening of the umbrella.

The protector includes a sleeve 22 of waterproof ma-

terial such as flexible, transparent plastic, gathered at one end and secured thereto to the inner surface of a relatively narrow, flexible cuff 24 of fabric or the like having at its ends cooperating gripper fastener elements 26, 28. The sleeve, for a short part of its length adjacent the cuff, is slit longitudinally as at 30, the cuff being formed at one end with a tongue-like extension 32 having element 28 thereon, the extension being extensible across the slit to interengage with element 26, and thereby close the cuff 10 tightly about the handle 16.

The other end of the sleeve is of a diameter sufficient to admit freely the folded canopy of the umbrella, thereby to extend the sleeve over a major part of the umbrella in covering relation thereto. On said other end, there is secured an annular collar 33 of metal or the like, that serves as a weight to cause the sleeve to be extended over the umbrella automatically when the umbrella is folded and positioned as in Fig. 1.

In use, and assuming that the umbrella is to be opened, one turns the umbrella up, and the weighted collar will shift to the position shown in Fig. 2, thus permitting the umbrella to be opened.

Fig. 8 shows a modified protector 34 including a sleeve 36 of flexible, transparent, waterproof plastic having at one end a weighted collar 38 like collar 33. At its other end, the sleeve is provided with gathers 40, that are formed through the use of elastic stitching 42 extending about the sleeve. The resiliently contracted sleeve end effectively grips staff 18 but at the same time, is easily shifted past the handle 16 when being applied or removed.

In Figs. 9—13, a second modification 44 is shown, this being adapted to enclose the folded sleeve 45 in a sectionally formed housing composed of a cuff and a collar that are releasably interlocked.

The cuff is composed of a pair of flat, semicircular disc members 46, 47 having confronting semicircular recesses in their straight, contacting inner edges receiving the staff 18. The arcuate outer edge of each member is formed with an end-to-end flange. Hinge 48 connects the members at one end of the flanges and formed on the flanges adjacent their other ends are radially and outwardly extending tabs or ears 49, 50, the inner surfaces of which may be knurled. A spring 51 is connected between the members adjacent the tabs and normally swings the members toward one another into gripping engagement with the staff.

Formed in the flanges of members 46, 47 are slot-like openings 52, 54 respectively, the openings being spaced circumferentially of the cuff, as best shown in Fig. 12.

A weighted collar 56 is also of flat, disc-like shape and has a large center opening 58 of a diameter that permits the collar to slide freely over the folded canopy portion of the umbrella. The collar is of one-piece formation and has a circumferential flange 60 which has an inwardly offset edge portion 62 formed at intervals spaced circumferentially thereof with outwardly directed lugs 64 engageable in openings 54.

The sleeve 45 is attached at its opposite ends to the cuff and collar, respectively. That end of the sleeve connected to the cuff is slit longitudinally at diametrically opposite locations to permit the cuff sections to be spread apart to a slight extent.

The cuff sections need only be spread apart slightly to disengage or engage lugs 64. Thus, and assuming that the collar is interlocked with the cuff as shown, one inserts the thumb and index finger in the space between the tabs and exerts pressure to spread the tabs. This swings the cuff members apart to free the collar, the collar gravitating to the other end of the umbrella staff to protectively enclose the folded canopy with the sleeve 45. When the sleeve 45 is to be folded again, the collar when shifted against the cuff will bias the cuff mem-

bers apart by reason of beveled or cam surfaces on the lugs 64.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An umbrella protector comprising a sleeve, a cuff on one end thereof adapted to grip an umbrella staff, and a weighted collar on the other end adapted to gravitate longitudinally of said staff to protectively enclose the canopy portion of the umbrella with said sleeve, said cuff being formed as a pair of cuff members hingedly connected, the cuff members and collar including means to interlock the same, said means disengaging on swinging of the cuff members apart.

2. An umbrella protector comprising a sleeve, a cuff on one end thereof adapted to grip an umbrella staff, and a weighted collar on the other end adapted to gravitate longitudinally of said staff to protectively enclose the canopy portion of the umbrella with said sleeve, said cuff being formed as a pair of cuff members hingedly connected, the cuff members and collar including means to interlock the same, said means disengaging on swinging of the cuff members apart, said means comprising lugs on the collar, the cuff sections having openings receiving the lugs.

3. An umbrella protector comprising a sleeve, a cuff on one end thereof adapted to grip an umbrella staff, and a weighted collar on the other end adapted to gravitate longitudinally of said staff to protectively enclose the canopy portion of the umbrella with said sleeve, said cuff being formed as a pair of cuff members hingedly connected, the cuff members and collar including means to interlock the same, said means disengaging on swinging of the cuff members apart, said means comprising lugs on the collar, the cuff sections having openings receiving the lugs, the cuff including a spring connected between the cuff sections and tensioned to yieldably urge the sections into engagement with one another.

4. An umbrella protector comprising a sleeve, a cuff on one end thereof adapted to grip an umbrella staff, and a weighted collar on the other end adapted to gravitate longitudinally of said staff to protectively enclose the canopy portion of the umbrella with said sleeve, said cuff being formed as a pair of cuff members hingedly

connected, the cuff members and collar including means to interlock the same, said means disengaging on swinging of the cuff members apart, said means comprising lugs on the collar, the cuff sections having openings receiving the lugs, the cuff including a spring connected between the cuff sections and tensioned to yieldably urge the sections into engagement with one another, said cuff sections and collar having abutting flanges.

5. An umbrella protector comprising a sleeve, a cuff on one end thereof adapted to grip an umbrella staff, and a weighted collar on the other end adapted to gravitate longitudinally of said staff to protectively enclose the canopy portion of the umbrella with said sleeve, said cuff being formed as a pair of cuff members hingedly connected, the cuff members and collar including means to interlock the same, said means disengaging on swinging of the cuff members apart, said means comprising lugs on the collar, the cuff sections having openings receiving the lugs, the cuff including a spring connected between the cuff sections and tensioned to yieldably urge the sections into engagement with one another, said cuff sections and collar having abutting flanges, the flange of the collar having an inwardly offset part telescoping in the cuff section flanges.

6. An umbrella protector comprising a sleeve, a cuff on one end thereof adapted to grip an umbrella staff, and a weighted collar on the other end adapted to gravitate longitudinally of said staff to protectively enclose the canopy portion of the umbrella with said sleeve, said cuff being formed as a pair of cuff members hingedly connected, the cuff members and collar including means to interlock the same, said means disengaging on swinging of the cuff members apart, said means comprising lugs on the collar, the cuff sections having openings receiving the lugs, the cuff including a spring connected between the cuff sections and tensioned to yieldably urge the sections into engagement with one another, said cuff sections and collar having abutting flanges, the flange of the collar having an inwardly offset part telescoping in the cuff section flanges, said lugs being formed on said inwardly offset part.
